UNITED STATES PATENT OFFICE.

JOHN BUCKLEY SEEL, OF MANCHESTER, ENGLAND.

SEWING-MACHINE FOR TUCKING.

SPECIFICATION forming part of Letters Patent No. 664,975, dated January 1, 1901.

Application filed March 5, 1900. Serial No. 7,394. (No model.)

To all whom it may concern.

Be it known that I, JOHN BUCKLEY SEEL, a subject of the Queen of Great Britain and Ireland, and a resident of 59 Chapel street, Great 5 Ancoats street, Manchester, county of Lancaster, England, have invented certain new and useful Improvements in Sewing-Machines for Tucking, (for which I have filed application for British patent, No. 2,953, dated February 14, 1900;) and I do hereby declare the following to be a full, clear, and exact description of the invention, such as will enable others skilled in the art to which it appertains to make and use the same.

15 This invention relates to the combination, with a sewing-machine, of means for forming "tucks" in or on textile fabrics.

Figure 1 is a side elevation. Fig. 2 is a plan. Fig. 3 is a cross-section on xx of Fig. 2. Fig. 20 4 is a plan to illustrate the formation of the fold. Fig. 5 is a front elevation showing the action of the gage or guider.

An ordinary sewing-machine A (indicated by dotted lines in Fig. 1) is used, preferably 25 in an inverted form, and secured to one of the uprights of the stand B by a screw a . The needle and presser-foot are then underneath, while the looper b is at the top. A cover-plate a^3 is held to the needle-plate a^2 by screws a^6 , passing through spiral springs 30 in compression between the cover-plate a^3 and the needle-plate a^2 , so that by turning the screws the distance of the cover-plate from the needle-plate a^2 may be varied to suit fabrics of different degrees of thickness.

The cloth in which the tuck is to be formed is folded over the tongue c' of the plate c , which is then slid forward, so as to bring the fold past the sewing-line a^5 of the needle. 40 The distance a^4 from the point of the tongue c' to the sewing-line of the needle determines the depth of the tuck. The cloth is fed past the needle in the direction of the arrow in Fig. 4. The part of the needle-plate just over the tongue c' , where the plait is formed to make the tuck, is cut away, as shown in Fig. 4. A drag pin or peg d , passing through the cover-plate a^3 and the needle-plate a^2 , puts a slight drag on the cloth and by keeping it taut on the tongue c' contributes to more perfect work and straighter feeding at

high speeds. The drag-pin d is set nearer to or farther from the tongue c' , according to the depth of the tuck to be formed. Several peg-holes are provided to enable this adjustment 55 to be made. The tuck is first formed over the point of the tongue c' . When the tongue is slid forward in the position shown in Fig. 4, the part of the fabric between d and the tongue will be subjected to friction or drag, 60 which will be greater or less, according as the pin d is nearer to or farther from the tongue. The plate c is mounted in fixed guideways, in which it may be slid longitudinally by the lever c^2 . One of the guide-bars c^3 is graduated to enable the plate to be readily set for any depth of tuck. An important feature of the invention is that the plate c and its fixed carrying-guides are mounted in such a manner as to be detached from the sewing-machine proper—as, for example, on a separate upright B' , extending from the floor, the base-plate of the machine, or formed as a rigid bracket connected to the upright B . Owing 70 to the absence of any arm or other obstacle 75 extending outward from the sewing-machine at its operative part to carry the tuck-forming appliance the cloth can hang or freely fall down under the table of the machine as the work proceeds both before and after the formation of the tuck. To prevent the cloth fouling the needle-bar or presser-foot when an inverted machine is used, a shield-plate s is carried by a lever d' , having its fulcrum at d^2 under the table of the machine. When 80 sewing is proceeding, the shield occupies the position shown in Fig. 1. When it is desired to gain access to the needle-bar, the shield s is swung outward away from the needle-bar. After the first tuck is formed the distance 85 apart of the succeeding tucks is determined by a gage or guider e . This consists of two thin plates of metal, which may be set at varying distances apart by means of set-screws. It is carried by a lever or arm e' , carried by 90 a block e^3 , hinged at e^2 on a plate e^4 , which can be slid longitudinally in guideways e^5 on the table of the machine by means of a lever e^6 . A spring e^7 , taking against flats on the block e^3 , holds the guide e either down to its 95 work (in the position shown in Fig. 1) or in its raised position when not in use and thrown 100

back to the left about its hinge-pin e^2 . The last tuck made is inserted between the plates of the guider e , as shown in Fig. 5, and as the work is fed forward this tuck acts as an automatic guider or gage for insuring the parallelism of the tuck actually being made with the one previously made. Marking-lines or other devices of a like nature for a similar purpose are thus unnecessary. The distance of the guider e from the sewing-line of the needle determines the pitch or distance apart of the tucks, and by sliding the plate e^4 any desired pitch may be obtained.

What I claim as my invention, and desire to secure by Letters Patent, is—

- 15 1. For forming tucks in textile fabrics the combination with a sewing-machine of the adjustable cover-plate a^3 the drag-pin d and the longitudinally-adjustable tongue-plate c ,
20 the latter mounted in fixed guideways detached from the sewing-machine proper at its operative part so as to present no obstacle to the hang or fall of the fabric in front of and

to the rear of the sewing mechanism substantially as set forth and shown.

2. For forming tucks in textile fabrics the combination with a sewing-machine of the adjustable cover-plate a^3 the drag-pin d the longitudinally-adjustable hinged guider or gage e and the longitudinally-adjustable independently-supported tongue-plate c , substantially as set forth and shown.

3. For forming tucks in textile fabrics the combination with an inverted sewing-machine of the shield s the adjustable cover-plate a^3 the drag-pin d the guider or gage e and the independently-supported longitudinally-adjustable tongue-plate c substantially as set forth and shown.

In testimony whereof I hereunto affix my signature in presence of two witnesses.

JOHN BUCKLEY SEEL.
